BODY VIBRATOR

Wesley D. Spencer, Los Angeles, Calif.

Application April 28, 1936, Serial No. 76,761

5 Claims. (Cl. 128—41)

My invention relates to a vibrator for the purpose of vibrating the human body. The objects of my invention are:

First, to provide a vibrator of this class in which the person treated stands on a platform with his feet, and thus the whole body is vibrated.

Second, to provide a vibrator of this class in which an electro-magnet causes mechanical vibration of the body;

Third, to provide a vibrator of this class in which one end of the platform upon which the person taking treatment stands rests on a floor, while the other end is supported by the electro-magnetic vibrator;

Fourth, to provide a vibrator of this class which provides ample strength for vibration for any purpose desired;

Fifth, to provide a vibrator of this class in which the connecting parts throughout are so arranged and constructed that a maximum of vibration efficiency is produced;

Sixth, to provide a vibrator of this class in which the vibrating structure is extremely compact of construction;

Seventh, to provide a vibrator of this class with means for supporting the person while being treated;

Eighth, to provide a vibrator of this class which is very simple and economical of construction and operation, durable, efficient and which will not readily deteriorate or get out of order.

With these and other objects in view as will appear hereinafter, my invention consists of certain novel features of construction, combination, and arrangement of parts and portions as will be hereinafter described in detail and particularly set forth in the appended claims, reference being had to the accompanying drawings and to the characters of reference thereon which form a part of this application in which:

Figure 1 is a side elevational view of my vibrator complete and ready for use; Fig. 2 is a sectional view from the line 2—2 of Fig. 1; Fig. 3 is a front end view of my vibrator complete; Fig. 4 is a sectional view on an enlarged scale from the line 4—4 of Fig. 3 showing some of the parts in elevation to facilitate the illustration; Fig. 5 is an enlarged sectional view from the line 5—5 of Fig. 3; Fig. 6 is a side elevational view of the electro-magnet and armature positioned in one side of the casing; Fig. 7 is a longitudinal sectional view from the line 7—7 of Fig. 6 showing some of the parts and portions in elevation to facilitate the illustration; Fig. 8 is a fragmentary sectional view from the line 8—8 of Fig. 6; Fig. 9 is a fragmentary sectional view from the line 9—9 of Fig. 6 and Fig. 10 is a transverse sectional view of the electro-magnet from the line 10—10 of Fig. 6.

Similar characters of reference refer to similar parts and portions throughout the several views of the drawings:

The platform 1, handle 2, handle shaft 3, switch 4, frame 5, vibrator casing 6, electro-magnet winding 7, electro-magnet laminated core 8, conductors 9, vibrator support 10, laminated armature 11, sponge rubber cushion 12, rubber casing 13, bar 14, and platform support 15, constitute the principal parts and portions of my body vibrator.

The platform 1 is preferably a suitable light weight board provided with a suitable covering on its upper surface and also preferably provided with a metallic trim 1a around its edge. It is preferably made narrower at its one end 1b so that it may be readily positioned in the frame 5 as will be hereinafter described. It is provided in its narrow end with a slot 1c in the middle thereof longitudinally of said board and with slots 1f and 1g extending transversely of said board from the slot 1c in opposite directions, and secured across the slots 1f and 1g are flexible canvass or rubber pads 1d on opposite sides of the slot 1c and extending over the slots 1f and 1g. Said members 1d are anchored by means of a board 1h around which the members 1d are mounted and the board secured by means of nails 1i. This slot 1c is adapted to permit the insertion of the bar 14 so that the narrow end of the board rests upon the supports 15 as will be hereinafter described.

The frame member consists preferably of pipe members 5 connected at their inner ends by pipe-T 3a then there are provided upright pipe members 5a which connect with the pipe members 5 by L's 5b. Connected to the lower ends of the members 5a are pipe-T's 5c which connect with pipe members 5d. Each of the members 5d at their extremities are provided with L's 5e and on the lower portions of these L members 5e are provided rubber cushions 5f. Secured in the upwardly extending member of the T 3a is a handle shaft 3 which extends upwardly and backwardly on an angle as shown best in Fig. 1 of the drawings, and on the upper end of which is mounted a T member 2a in the horizontal end portions of which are mounted pipe members which are covered with rubber pads 2b. Mounted in the T 2a is an electrical switch member 4, which is provided with contacts 4a which contact with a conductor 4b which extends downwardly through the shaft 3 and connects with a conductor 4c which connects with conductors 9 which lead to the electro-magnetic winding 7 in the casing 6.

The casing 6 consists of two double interchangeable casing members, each of which is provided with an inverted V-shaped lug 6a which are adapted to fit together to form a support for the support 10 which is a strong fabric tape member which passes around the lug member 6a.

and outwardly through slots in the upper edge of the casing and loops over a lug 18a secured on the lower side of the T 3a shown best in Fig. 3 of the drawings, thus providing a strong but slightly flexible support for the casing 6. Each member of the casing 6 is also provided with a lug 6b which extends inwardly some distance from its outer side, some distance from its upper end and with another lug 6c which extends 10 inwardly some distance and at the lower corners of each casing member 6 are provided lugs 6d which come nearly together but leave a space 6e through which the bar 14 extends.

Mounted in this casing 6 is a laminated core 8 which is substantially M-shaped provided with a large central portion around which the winding 7 is mounted and with two side members outwardly of said winding as shown best in Fig. 10 of the drawings. These interchangeable casing members 6 are secured together by means of bolts 6f and 6g. The bolts 6f being tap bolts while the bolts 6g extend clear through the casing as shown best in Fig. 7 of the drawings to facilitate the separation of the casing for removing the electromagnet and armature therefrom.

Positioned in the casing in close juxtaposition with the electro-magnet, consisting of the winding 7 and core 8, is an armature consisting of a laminated armature member 11 which extends 30 nearly the full width of the casing, and against the lower side there is provided a cushion of sponge rubber 12, and around the sponge rubber and the laminated core 11 is a rubber casing or covering 13. The laminations of the armature 11 are secured together by means of rivets 11a which pass through the metallic bar 14 inserted in the middle of said laminated core and extending outwardly through the opening 6e shown best in Fig. 7 of the drawings. The outer end of 40 this bar 14 is provided with extending branches which form support 15 for the platform 1, the platform being supported on these supports 15 on the cushion members 1d over the openings 1f and 1g of the platform 1 as shown best in Figs. 45 2, 3, and 4 of the drawings, it being noted that the platform 1 has a rubber cushion 1e to cushion it upon the floor or other surface upon which it rests.

The operation of my body vibrator is as follows: Electric current is supplied to the winding 7 from a source of electric energy through electrical conductor 4c which connects with the conductor 4b which magnetizes the core 8 which draws the armature 11 and causes it to vibrate. 50 It is cushioned by the sponge rubber cushion 12 and further cushioned by the rubber covering 13 surrounding the armature 11, thus providing rapid vibration of the armature 11 which causes the vibration of the bar 14 and supports 15 are 55 therefore vibrated and the person receiving the treatment standing upon the broad portion of the platform which receives this vibration and inasmuch as his feet and whole body is effectively vibrated, and he supports himself by holding onto 60 the rubber handle portions 2b of the handled 2. He can turn off the current by raising the switch 4 until the contacts 4a are disengaged from the conductor 4b and can turn it on again by depressing the same. The cushions 1d aid in the 65 vibration as the platform is yieldably suspended upon the supports 15 and the supports 15 are yieldably suspended in the casing 6 by means of the rubber cushions and the casing 6 is also yield-

ably suspended upon the tape support 18 in connection with the frame.

Though I have shown and described a particular construction, combination and arrangement of parts and portions, I do not wish to be limited to this particular construction, combination, and arrangement, but desire to include in the scope of my invention, the construction, combination, and arrangement substantially as set forth in the appended claims.

Having thus described my invention, what I claim as new and desire to secure by Letters Patent is:

1. In a body vibrator, a vertically disposed frame with an upper horizontal portion, an electro-magnetic vibrator suspended on said upper horizontal portion provided with a rubber cushioned armature, a support secured to said armature and suspended on said vibrator, and a substantially horizontal platform with one end flexibly supported on said suspended support. 15

2. In a body vibrator, a vertically disposed frame with an upper horizontal portion, an electro-magnetic vibrator suspended on said upper horizontal portion provided with a rubber cushioned armature, a support secured to said armature and suspended on said vibrator, a substantially horizontal platform with one end flexibly supported on said suspended support, and a handle extending upwardly from said upper horizontal over said platform. 25

3. In a body vibrator, a vertically disposed frame, a casing enclosing an electro-magnet consisting of a laminated core and a winding suspended on the upper portion of said frame, an armature in vibrating relation with said core in said casing, a rubber cushion on the opposite side of said armature from said core and engageable with the end of said casing, a supporting member secured to said armature and extending down through said casing, and a substantially horizontal pivotally positioned platform with one end supported on said supporting member. 40

4. In a body vibrator, a vertically disposed frame, a casing enclosing an electro-magnet consisting of a laminated core and a winding suspended on the upper portion of said frame, an armature in vibrating relation with said core in said casing, a rubber cushion on the opposite side of said armature from said core and engageable with the end of said casing, a supporting member secured to said armature and extending down through said casing, a substantially horizontal pivotally positioned platform with one end supported on said supporting member, and cushion means between said support and said platform. 50

5. In a body vibrator, a vertically disposed frame, a casing enclosing an electro-magnet consisting of a laminated core and a winding suspended on the upper portion of said frame, an armature in vibrating relation with said core in said casing, a rubber cushion on the opposite side of said armature from said core and engageable with the end of said casing, a supporting member secured to said armature and extending down through said casing, a substantially horizontal pivotally positioned platform with one end supported on said supporting member, cushion means between said support and said platform, and said casing composed of two interchangeable members. 60

WESLEY D. SPENCER.
